UNITED STATES PATENT OFFICE.

THOMAS S. COOPER, JR., OF CHARLESTON, WEST VIRGINIA, ASSIGNOR TO KOOPER DAMPER CO. OF PHILADELPHIA, PENNSYLVANIA.

AUTOMATIC DAMPER.

Application filed September 9, 1921. Serial No. 499,364.

To all whom it may concern:

Be it known that I, THOMAS S. COOPER, Jr., a citizen of the United States, residing at Charleston, in the county of Kanawha and State of West Virginia, have invented 5 certain new and useful Improvements in Automatic Dampers; and I do declare the following to be a full, clear, and exact description of the invention, such as will enable 10 others skilled in the art to which it appertains to make and use the same.

My invention aims to provide a simple, inexpensive and practical thermostatic damper for use in dwellings, factory and mill stacks, 15 etc., the construction being such that the damper plate, the shaft on which said plate is mounted, and the thermostat constitute a unitary article so that loss of parts prior to installation will not take place.

20 A further object of the invention is to provide means whereby the damper may be adjusted by hand whenever advisable and held in adjusted position by unique means.

With the foregoing in view, the invention 25 resides in the novel subject matter herein-after described and claimed, the descriptive matter being supplemented by the accompanying drawings.

Figure 1 is a plan view of a damper constructed in accordance with my invention, showing the same applied to a smoke pipe, the latter being illustrated in vertical section.

Figure 2 is a vertical section as indicated 30 by line 2—2 of Fig. 1.

Figure 3 is a horizontal section taken on line 3—3 of Fig. 1.

Figure 4 is a detail elevation, illustrating 35 more particularly the manual adjusting means for the damper.

Figure 5 is a detail perspective view of the construction at one end of the supporting shaft.

In the drawings above briefly described, 40 the numeral 1 designates a short length of smoke pipe which may well be a part of an ordinary stove pipe, or part of a smoke stack such as those used in factories and mills. In installing my invention in the pipe 45 1, I form a relatively small opening 2 at one side thereof and a much larger opening 3 at the diametrically opposite side, the metal

at one side of the opening 3, preferably its lower side, being split vertically as indicated at 4 and terminating in a notch 5 communicating with said opening. The supporting shaft 6 of the damper extends across the pipe 1 and has one end rotatably received in the opening 2, while the other end of said shaft is provided with an enlarged head 7 of approximately circular form, said head being received in the opening 3 and being provided with a suitable handle 8. By means of suitable bearings 9, the damper plate 10 is mounted on the shaft 6 so that the two may turn relatively, and said plate is provided with an outwardly extending finger 11 which is received in a notch 12 in the peripheral portion of the head 7, said notch preferably extending throughout one-quarter 50 of the circumference of said head. Thus, the damper will be limited in its opening and closing movement and by viewing the finger 11 from the exterior of the pipe, the angle at which the damper plate is setting, 55 can be readily seen. The periphery of the head 7 is formed with a circumferentially extending groove 13 which receives the metal surrounding the opening 3, whereby to hold the head against axial movement 60 and consequently preventing removal of the shaft 6. In order that the head may be positioned in the opening 3, it is necessary to turn the metal at opposite sides of the split 4 outwardly. This having been done, the 65 head may be easily inserted, after which the metal is bent back in place. The outer side wall of the groove 13, in the embodiment of the invention herein shown, is provided with a 70 inwardly extending oppositely tapered cam 14 and directly opposite this cam, the other wall of said groove is formed with a gradually deepening notch 16. When it is desired to rotate the head and shaft, in order that the damper plate 10 may be set by 75 hand, the handle 8 may be used. During this operation, the cam 14 will spring the metal of the pipe 1 into the notch 16 and thus the head will be frictionally bound in any position to which it may be moved. In 80 one position of the shaft, the cam 14 may snap into the notch 5.

The damper plate 10 is provided with a longitudinally extending slot 17 whose end

portions are spanned by two of the bearings 9, these bearings as well as the others being only of semi-circular form, but the series of bearings are so related by disposing them alternately at opposite sides of the axis, that the plate 10 is rockably mounted in the desired manner. Received within the slot 17 and wrapped around the shaft 6 is a helical thermostat 18, one end of this thermostat 10 being connected with the damper plate by passing said end (designated by the reference numeral 19) through a slot 20 in one of the bearings 9. The other end of the thermostat is pinned or otherwise secured 15 to the shaft as indicated at 21. Two suitable metals having different coefficients of expansion are used in constructing the thermostat 18, so that it will be acted upon by excess heat to close the damper plate 10 across the pipe 1, while reduction in temperature will cause the inherent resiliency of the thermostat to return said plate to an open position. The finger 11 and the end walls of the notch 12 serve to limit both the 20 opening and closing movement of the damper plate and the finger also serves as an indicator so that the position of the damper may be seen from the outside of the pipe 1, permitting manual adjustment to be made 25 whenever desirable by means of the handle 8.

From the foregoing, taken in connection with the accompanying drawing, it will be seen that a comparatively simple and inexpensive thermostatic damper has been provided, yet one which will be highly efficient and desirable in use, particular attention being directed to the fact that the damper as manufactured and placed on sale constitutes a single unit, all parts thereof being 30 connected with each other in such manner that they cannot become accidentally detached and lost. This is highly advantageous from a commercial standpoint, as it facilitates packing, demonstration in sales rooms and stores, and delivery to the point at which it is to be used.

Since excellent results have been obtained from the details disclosed, they are preferably followed, but it is to be understood 50 within the scope of the invention as claimed, that numerous changes may be made.

I claim:

1. The combination with a shaft having a handle, and a thermostatic damper rotatable on said shaft; of a head on one end of said shaft adapted to be rotatably received in an opening in the pipe in which the damper is used, said head having a circumferential groove to receive the metal at the edge of the opening, one wall of said groove having an inwardly extending cam and the other wall of said groove being provided with a notch opposite said cam.

2. The combination with a pipe having 65 diametrically opposed openings, a shaft ex-

tending across said pipe through said openings and having a handle, and a thermostatic damper on said shaft; of a head on one end of said shaft, rotatable in one of said openings, said head having a circumferential groove to receive the metal at the edge of said opening, which metal is formed with a notch, one wall of said groove having an inwardly extending cam adapted to be received in said notch, the opposite wall of said groove having a notch opposed to said cam.

3. The combination with a shaft having a handle and a thermostatic damper on said shaft; of a head on one end of said shaft 80 adapted to be rotatably received in an opening in a pipe in which the damper is used, said head having a notch extending throughout approximately ninety degrees of its circumference, and a finger on the 85 damper plate received in said notch to limit the movement of said damper plate, means being provided to hold the head normally against rotation.

4. A damper shaft having a head adapted to be rotatably mounted in an opening in the wall of a conduit when the shaft is extended transversely through the conduit, said head having a peripheral groove for receiving the material surrounding the opening, one wall of the groove having an inwardly extending cam for engaging the wall of the conduit and the other wall of the groove being provided with a notch disposed opposite said cam to permit the material of the conduit wall to be forced into the notch and provide a friction lock yieldably preventing rotation of the damper shaft.

5. The structure set forth in claim 4 having a segment of the periphery of said head cut away to provide a notch, a damper plate carried by said shaft, and a stop finger damper plate extending from said damper plate and extending into the notch of the 110 shaft head.

6. A damper embodying a plate provided with a central slot to accommodate a spring, bowed straps extending across said slot, the straps being bowed on opposite sides of the 115 faces of the plate to provide bearings, a shaft extending across the plate longitudinally of the slot with the straps engaging the shaft, for rotatably mounting the plate on a shaft, and a finger extending from the periphery of said plate longitudinally of the shaft and projectable through an opening in a pipe having the damper mounted therein, said finger being disposed in a plane with the plate so that it will serve as an indicator to disclose the angle at which the plate is disposed in the pipe, said finger also functioning as a stop for engaging spaced abutments to limit the rotation of the plate.

7. The combination with a shaft having a handle, and a damper on said shaft; of a head on one end of said shaft adapted to be rotatably received in an opening in the pipe 5 in which the damper is used, said head having a circumferential groove to receive the metal at the edge of the opening and said head being provided with cam means for frictionally engaging metal of the pipe about the opening and yieldably holding 10 the shaft against rotation.

In testimony whereof I have hereunto set my hand.

THOMAS S. COOPER, JR.
